UNITED STATES PATENT OFFICE.

AUGUSTUS J. PEPIN, OF GRAND FORKS, NORTH DAKOTA.

COMBINATION AUTO TABLE AND TRUNK.

Application filed April 21, 1925. Serial No. 24,844.

To all whom it may concern:

Be it known that I, AUGUSTUS J. PEPIN, a citizen of the United States, residing at Grand Forks, in the county of Grand Forks 5 and State of North Dakota, have invented certain new and useful Improvements in Combination Auto Tables and Trunks; and I do hereby declare the following to be a full, clear, and exact description of the invention, such as will enable others skilled in the art to which it appertains to make and use the same.

This invention relates to a combination table and trunk primarily though not necessarily adapted for use while autoing and camping.

A particular object is to provide a novel construction adapted to serve dually as a table or as a trunk or box, which may be 20 carried on the automobile as an accessory.

Another object is to provide a novel construction wherein all of the joints are efficiently trussed or braced when the article is in table form.

25 A further object is to provide a novel construction wherein the table may be effectively arranged into different lengths.

A still further object is to provide a construction wherein the bracing means for 30 the different parts when used in table form, may consist of brackets which latter may carry the latching or connecting means.

Various additional and servient objects and advantages will become apparent from 35 a consideration of the description following taken in connection with accompanying drawings illustrating an operative embodiment.

In said drawings:—

40 Figure 1 is a view of the device in trunk form and in front elevation;

Figure 2 is a plan view of the device in trunk form;

Figure 3 is a sectional view taken on the 45 line 3—3 of Figure 1;

Figure 4 is a side elevation of the device as used in table form of maximum length;

Figure 5 is a longitudinal sectional view 50 of the device as used in table form of minimum length;

Figure 6 is a cross sectional view taken on the line 6—6 of Figure 5.

Figure 7 is a perspective view of one of the intermediate sections;

55 Figures 8 and 9 are detail views taken on the lines 8—8 and 9—9 of Figure 3;

Figure 10 is a detail sectional view taken on the line 10—10 of Figure 2, and

Figure 11 is a detail sectional view taken on the line 11—11 of Figure 3.

Referring specifically to the drawings, the device primarily comprises panels 10 and 11 which form the ends of tables as in Figures 4 and 5 and which form the top and front, of a box, chest or trunk as well shown 65 in Figure 3. Said panels 10 and 11 are supplemented by additional similar panels 12, forming intermediate panels, to extend the table as in Figure 4 and form the bottom and rear wall of the trunk as shown in 70 Figure 3. Similar end walls or panels 13 are also used to complete the trunk but which are not used in the case of the table. Said walls or panels 10, 11 and 12 may be made of any suitable size and material, for 75 instance wood as shown, metal or otherwise.

The walls or panels 10, 11 and 12 are adapted for swinging or hinge movement so as to aline to form a table top as in 80 Figure 4, and are normally held against 85 such movement and in box or trunk form by the end walls 13. Such end walls 13 are removable and have studs 14 at the sides and bottom removably penetrating eyes 15 of keepers 16 screwed or otherwise fastened to the panels 11 and 12, see Figures 3, 9 and 11. In addition, and preferably 90 adjacent the top, the end panels 13 have plates 17 fastened thereto through which latches 18 are pivoted at 19, see Figures 3 and 8. Latches 18 are of hook form and 95 their hooks are adapted for passage through eyes or openings 20 of keepers 21, similar to the keepers 16 and fastened to the wall 11 and to the wall 12 parallel therewith. 100 The said latches 18 normally prevent unfolding of the walls 11 and 12 towards parallelism or table top form but they permit the top 10 to be moved relatively to permit access to the trunk.

105 Wall 10 at the rear longitudinal edge and the walls 11 and 12 at their adjacent edges are pivotally and detachably connected together by appropriate hinges generally designated 22 and detailed in Figure 10. These hinges comprise leaves 23 and 24, screwed or otherwise fastened to the appropriate panels. The leaves 24 have angular offsets 25 provided with eyes or openings 26 through which the other leaves 23 pass loosely, and beyond which they preferably have angular offsets 27 to coat

with that at 25 so that the leaves may be joined together in such manner that although separable from each other, they will nevertheless permit swinging of the 5 panels without undue danger of separation or detachment. At the front, panel 10 has a suitable fastening as at 28 carrying a hasp 29 pivoted at 30 and adapted for coaction with a staple 31, in the usual manner, 10 carried by the panel 11 adjacent its upper edge, and which staple of course may receive a suitable padlock or equivalent device.

Carried by each of the panels 10 and 11 15 is a suitable leg or support generally designated 32 and which in the case of the trunk is normally compactly folded with respect thereto as well as shown in Figure 3 and also Figures 1 and 2. These devices 32 each 20 comprises a pair of spaced legs joined at their proximo ends by braces or bridges 34. Also at such proximo ends, the legs 33 pivotally connected by screws or the like 35 to L-shaped hinged leaves 36 fastened to 25 the panels 10 and 11. Such legs, as shown in Figures 4 and 5 are adapted to assume and be limited in movement to a table supporting position, preferably at the slight angle shown. To this end, links 37 and 38 30 are pivotally connected together as at 39 and respectively pivoted at 40 and 41 to the legs 33 and to the panels 10 and 11. Such links are normally compactly folded as shown in Figures 1, 2 and 3 but are limited 35 to the unfolded position of Figures 4 and 5 through the abutment of a stop-lug 42 on the links 37, with the links 38.

Suitably fastened to the panels 10 and 11 40 as shown are brackets 43 while brackets 44, which in effect are substantially double the form of brackets 43, are appropriately fastened to the intermediate panels 12. These brackets 43 and 44 in the alined or table position of Figure 4 have abutting portions 45 disposed at a right angle to the panels. Said portions 45 serve as keeper portions 45 in that they have registering openings 46 therethrough, through which the hook 47 of a latch 48 is adapted to pass to rigidly 50 secure them together as well shown in Figure 5. The latches 48 are pivotally mounted as at 49 in any suitable manner on the brackets 43 and 44. On the pivot elements or pins 49, expansive coil springs 50 are 55 mounted which engage the brackets 43 and 44 and the latches 48 in such manner that the hook 47 is urged in a direction away from the panel by which it is carried so as to be urged in other words to fastening position.

In use, the device in the trunk form as 60 shown in Figures 1, 2 and 3, is adapted to be carried on the running board, at the rear or otherwise on an automobile or vehicle. 65 It may thus serve as a trunk and access to

the interior thereof is had by unfastening the hasp 29 from the staple 31 and then swinging the top or panel 10 upwardly and rearwardly on the associated hinges 22. At the destination, when camping, or otherwise, 70 if the device is to be used as a table, after the panel 10 has been opened in the manner previously suggested, the leg devices or supports 32 may then be unfolded or projected, but which unfolding or projecting 75 may be delayed until panels 10, 11 and 12 are in alinement, as preferred. With the panel 10 open, the latches 18 are swung into released position and thereafter panels 10, 11 and 12 may be swung on their hinges 22 80 into alinement as in Figure 4, being limited to the alined position by the abutment of the keeper portions 45 of brackets 43 and 44. When such alinement and abutment is effected, the hooks 47 of latches 48 automatically pass through the registering openings 46 and thus lock brackets 43 and 44 together and accordingly locking the panels 10, 11 and 12 in alined position or table 85 form.

The table of Figure 4 is of maximum length and in the event a shorter table is desired, the intermediate sections or panels 12 may be removed so that the sections or panels 10 and 11 will be directly connected 90 together by the associated latch 48 as shown in Figure 5. Such sections or panels 12 may be readily disengaged through the disengagement of the leaves 23 and 24 of the 95 associated hinges 22. If desired, instead of both of the sections or panels 12 being removed, one of them may be permitted to remain so that the table top would comprise a section 10, 11 and 12.

Attention is called to the fact that the 100 leg devices 32 in their folded relation are disposed intermediate the brackets 43 as best shown in Figure 3, so as to be protected particularly against danger of lateral distortion, by such brackets.

It will be furthermore apparent that as the legs 33, the leg brackets comprising the links 37 and 38, and the brackets 43 and 44 and the other parts comprising the means for forming the table top, are exterior of 115 the device when in trunk form, these parts will in no wise restrict the trunk for baggage carrying, and furthermore the size of the panels 10, 11, and 12 forming the top 120 of the table will be kept clean by being on the interior of the trunk form.

Various changes may be resorted to provided they fall within the spirit and scope of the invention.

What is claimed is:

1. An apparatus of the class described having panels adapted to coact in the formation of an article, means permitting movement of said panels into table-top form, brackets limiting movement of said panels 130

to the latter form, and latches carried by said brackets for coaction with each other to secure the panels in table-top form, said brackets having keeper portions adapted for 5 direct engagement, and said keeper portions provided with alining openings for reception and coaction with the latches.

2. An apparatus of the class described having panels, means detachably connecting said 10 panels and pivotally connecting them to permit use thereof in a plurality of articles, one of said articles being a table, brackets on said panels having keeper portions adapted for abutment in the table form, and 15 latches on the brackets coacting with the keepers.

3. An apparatus of the class described having panels, means detachably connecting said panels and pivotally connecting them to 20 permit use thereof in a plurality of articles, one of said articles being a table, brackets on said panels having keeper portions adapted for abutment in the table form, latches on the brackets coacting with the keepers, and 25 supports for certain of the panels in the latter position, said supports being carried by certain of the panels and foldable with respect thereto.

4. An apparatus of the class described having panels, means detachably connecting 30 said panels and pivotally connecting them to permit use thereof in a plurality of articles, one of said articles being a table, brackets on said panels having keeper portions adapted for abutment in the table 35 form, latches on the brackets coacting with the keepers, and supports for the panels in the latter position, said supports being carried by certain of the panels and foldable with respect thereto and intermediate certain of said brackets for protection by the latter.

5. An apparatus of the class described comprising panels detachably and hingedly connected together whereby they may form 40 walls of a trunk and may also serve as a table top, brackets carried by the panels adapted for engagement to limit their movement to table top form, and fastening elements coacting with the brackets to secure 45 the panels rigidly in the latter form, said brackets and fastening elements being exterior of the device when in trunk form.

In testimony whereof I affix my signature.

AUGUSTUS J. PEPIN.
